Charles Butterworth
Inventor

United States Patent Office.

CHARLES BUTTERWORTH, OF MIAMISBURG, OHIO, ASSIGNOR TO HIMSELF AND JACOB KERCHER.

Letters Patent No. 64,946, dated May 21, 1867.

IMPROVEMENT IN LIFTING-JACK.

The Schedule referred to in these Letters Patent and making part of the same.

TO ALL WHOM IT MAY CONCERN:

Be it known that I, CHARLES BUTTERWORTH, of Miamisburg, in the county of Montgomery, in the State of Ohio, have invented a new and improved Carriage-Jack; and I do hereby declare that the following is a full and exact description thereof, reference being had to the accompanying drawing, and to the letters of reference marked thereon.

The nature of my invention consists in the construction of the upright parts as usual, and in attaching to the side of the base part supporting pieces with horizontal planes for a roller, thereby forming a movable fulcrum for the lever.

To enable others skilled in the art to make and use my invention, I will proceed to describe its construction and operation.

The figure represents a side view of the carriage-jack.

B represents the upright supported by the base G. It has a square orifice for the reception of the part A, and to the side is attached a steel spring-catch, C, which catch is attached to the upright by a screw at its lower end, and near the top is a projection, m, extending inward, and which enters holes within the upright A, and holds the upright at the altitude to which it is raised by the lever, and to let it down the upper part is grasped by the fingers, (the weight being relieved by pressure on the lever,) and drawn outwards into the guide D; thus relieved it descends. The side of the upright B is slotted for the lever E, and on either side of this slot are attached supporting pieces F, having plane surfaces on which rests the roller n. This roller is attached to the lever by a metallic strap passing over a groove in the centre of the roller. The end of the lever is connected to the upright A by a pin, o, which passes through the slotted end of the upright. The dotted lines indicate the relation of the lever and upright.

Operation.

The jack being placed under a carriage-axle the lever is depressed, thus elevating the upright A, the spring-catch serving to hold it at the point to which it is elevated. At each movement of the lever the roller serving as a fulcrum to the lever changes position on the plane of the supporting pieces.

What I claim as my invention, and desire to secure by Letters Patent, is—

The combination and arrangement of the uprights A and B, the lever E with its fulcrum-roller n, and the supporting pieces F, constructed substantially as described and for the purpose specified.

CHARLES BUTTERWORTH.
